CLAIM

The ornamental design for a power injection system face plate, as shown and described.

DESCRIPTION

FIG. 1 is a rear perspective view of the design;

FIG. 2 is a front view;

FIG. 3 is a right side view;

FIG. 4 is a left side view;

FIG. 5 is a top view;

FIG. 6 is a bottom view; and,

FIG. 7 is a rear view.

The broken line showing of the power injection system face plate is for the purpose of illustrating the environmental structure and forms no part of the claimed design.
